UNITED STATES PATENT OFFICE.

JOHN LIGHTON AND PATRICK H. BRENNAN, OF SYRACUSE, NEW YORK,
ASSIGNORS TO THE JOHN LIGHTON MACHINE COMPANY, OF SAME PLACE.

MAIL-BAG-CORD FASTENER.

SPECIFICATION forming part of Letters Patent No. 434,875, dated August 19, 1890.

Application filed July 23, 1890. Serial No. 359,633. (No model.)

To all whom it may concern:

Be it known that we, JOHN LIGHTON and PATRICK H. BRENNAN, of Syracuse, in the county of Onondaga, in the State of New York, have invented new and useful Improvements 5 in Mail-Bag-Cord Fasteners, of which the following, taken in connection with the accompanying drawings, is a full, clear, and exact description.

10 Our invention relates to an improved fastener particularly applicable for fastening mail and other bags; and it has for its object the production of a simple, effective, and durable device which positively prevents the 15 opening of the bag and is readily adjusted to open or close the bag; and to this end it consists, essentially, in a guide through which the cord is passed, a support upon which the cord rests, and a movable holder above said 20 support for frictionally engaging the cord and retaining the same in its adjusted position.

The invention also consists in the detail construction and arrangement of the parts, all as hereinafter more particularly described, 25 and pointed out in the claim.

In describing this invention reference is had to the accompanying drawings, forming a part of this specification, in which like letters indicate corresponding parts in all the 30 views.

Figure 1 represents a top plan view of an open bag and our improved cord-fastener operatively secured to a cord for gathering together the mouth of the bag. Figs. 2 and 3 35 are respectively top and bottom plan views of our improved cord-fastener. Figs. 4 and 5 are vertical sectional views taken on the respective section-lines $x-x$ and $y-y$, Fig. 2; and Fig. 6 is a longitudinal vertical sectional 40 view taken on line $z-z$, Fig. 2, of our improved fastener.

A represents any suitable construction of bag, which is here shown as an ordinary mail-bag having its upper part provided with a 45 series of perforations or openings a , through which is passed a suitable cord B, of any desirable construction.

C represents our improved fastener, through which are passed the ends b of the cord B. The 50 fastener C are provided with a guide c for receiving the cord B, and as preferably con-

structed this guide is formed of metal bent into a U shape in cross-section, as best seen in Figs. 4 and 5.

To allow the ready passage of the cord, the 55 opposite extremities of the guide c are preferably open and are provided with suitable partitions c' , which firmly support or brace the upper part of the guide and form separate channels or ways through the guide for 60 the opposite extremities of the cord, thus directing each to its own wheel and preventing any interference one with the other, by which they might become knotted or twisted together and jammed in the guide. The base-plate c^2 of the fastener C forms a support upon which the cord rests, and, as best seen in Figs. 4 and 6, this base-plate is preferably formed with a pair of depressed grooves c^3 , 65 concaved both laterally and longitudinally 70 for receiving the cord and retaining the same with a greater power than would otherwise be the case.

Above the grooves c^3 are the holders D, which are movable toward and away from 75 the cord for frictionally engaging the same and retaining it in its adjusted position. As constructed these holders are cam-shaped and consist of a wheel eccentrically pivoted at its forward portion by a pin d to the walls 80 of the guide c and formed with a concaving face or periphery d' , adapted to fit around the cord and firmly holding the same by the great amount of bearing-surface.

When the bag is closed, it will be understood that the same is gathered together by forcing the fastener along the cord B until it can go no farther. In order to open the bag it becomes necessary for the cord to move in the direction shown by the arrow 1, Fig. 6, 90 and upon reference to said figure it will be noted that the pivot-point d of the holder D is at the forward portion thereof, and that such movement of the cord tends to roll the holder in the direction shown by the arrow 2, Fig. 6, whereupon the cord is more tightly impinged than when no strain is present. It 95 will thus be understood that the greater the strain from the inside of the bag to open the same the greater the force with which the cord- 100 fastener holds the bag.

When the operator desires to open the bag,

he rolls the holders upward, or, in other words, in a direction opposite to that indicated by arrow 2, whereupon the fastener can be readily shifted to its extreme backward or any other 5 desired adjustment.

c^4 represents an opening in the upper part of the guide c for the purpose of enabling the operator to actuate the holding-eccentrics D by his thumb and fingers while the hand is 10 in engagement with the fastener for adjusting the same to its desired position.

The pivot-pin upon which the holders or wheels D are eccentrically mounted is placed nearer the forward edge c^7 of the opening c^4 15 than to the rear edge c^8 , so that while the longer radius of the holders may pass the opposite edge c^8 of the opening it cannot pass the edge c^7 , which thus acts as a stop to hold the wheels in retracted position, as shown by dotted lines in Fig. 6, when the cord may be 20 freely moved in either direction.

The operation of rolling backward the eccentric D for the purpose of enabling the opening of the bag is, however, greatly facilitated by first pulling the cord backward, or, 25 in other words, in a direction opposite to that shown by the arrow 1, whereupon the eccentric is rolled upward by the movement of the cord, and said eccentric can then readily be 30 engaged by the operator, thereby greatly facilitating the unlocking of the fastener.

An important feature of my improved fastener is that while the opening in the top of the guide gives ready access to the holders, 35 the pin upon which they are mounted is so located that when the holders are clamping the cord they lie substantially within the guide. Any danger of accidental loosening of the holders and consequent opening of the 40 bag is thus most effectively obviated.

As preferably constructed, the base or bottom wall c^2 of the fastener C is formed of a separate piece from the remaining portion, and is secured thereto by ears c^5 , formed upon 45 the lower edge of the side of the guide and registered with openings c^6 in the said bottom wall c^2 . The side edges e of this bottom wall are lapped upon the lower face of said wall, with a space e' interposed between the 50 adjacent faces of said bottom wall and the side edges. Moreover the rear edge e^2 is also

lapped upon the bottom wall, as best seen in Fig. 6, thus forming a guide for receiving a suitable tag F , upon which is printed the name of the railroad and the direction in 55 which the mail-bag is to go, or any other suitable information or mark to designate one bag from another.

The concaved depressions forming the grooves c^3 in the upper side of the base-plate $6c$ c^2 form, also, Figs. 4 and 6, corresponding converse projections on the under side of said plate, which extend into the tag or label holding space and act to slightly bend the label, and thus secure it more firmly in place. 65

The parts of our invention are very simple in construction and operation, since the guide c and receiver e' are formed of sheet metal and are secured together at a minimum cost of expense, and the wheels D are also very 70 cheap, strong, durable, and effective.

The object of our invention will be readily perceived from the foregoing description and upon reference to the drawings, and it will be readily understood that the detail construction and arrangement of its parts may be somewhat varied from that described without departing from the spirit of our invention. 75

Having thus fully described our invention, 80 what we claim as new, and desire to secure by Letters Patent, is—

The combined cord-fastener and label-holder, consisting of a guide having separate channels for the cord, a base-plate having a groove 85 concaved longitudinally and laterally in each channel, and eccentric holders arranged to press the cord into such grooves, the base-plate having its sides and one end bent inward to co-operate with convex projections 90 under the plate in holding the label, substantially as described.

In testimony whereof we have hereunto signed our names, in the presence of two attesting witnesses, at Syracuse, in the county 95 of Onondaga, in the State of New York, this 21st day of July, 1890.

JOHN LIGHTON.

PATRICK H. BRENNAN.
